UNITED STATES PATENT OFFICE.

JOSHUA DAVIES, OF MUSKEGON, MICHIGAN.

DESIGN FOR HITCHING-POST.

Specification forming part of Design No. 7,801, dated October 13, 1874; application filed October 1, 1874.
 [Term of Patent 7 years.]

CASE C.

To all whom it may concern:

Be it known that I, JOSHUA DAVIES, of Muskegon, in the county of Muskegon and State of Michigan, have invented a Design for a Cast-Iron Hitching-Post, of which the following is a specification.

The nature of my invention is fully represented in the accompanying photographic illustration, to which reference is made.

A represents the pediment, consisting of an octagonal plinth with a base-molding, resting on a flat circular base-plate. B is a column, tapering, octagonal for the lower two-thirds, and circular in cross-section above, with a circular molding vertically fluted, as at A', interposed between its base and the pediment A. The octagonal portion of the column has a sunken panel in each face, while the upper

part is foliated in alto-relievo, as at B', and is surmounted by a flaring and fluted capital, C, which supports the neck and head D of a horse.

I am aware that hitching-posts have frequently been surmounted by or with a horse's head, and disclaim the invention, or rather the application thereof, to a hitching-post of any ordinary form; but

What I claim as my invention, and desire to secure by Letters Patent, is—

The design for a hitching-post, substantially as represented and described.

JOSHUA DAVIES.
